WRINGER

Charles B. Williams, Shaker Heights, Ohio

Application September 21, 1933, Serial No. 690,374

46 Claims. (Cl. 68—32)

This invention relates to a wringer for laundry purposes, and especially to a household laundry wringer which utilizes rotating pressure rolls to squeeze the water from the garments. This case 5 is a continuation in part of applicant's copending cases 503,891 and 518,415, filed December 22, 1930, and February 26, 1931, respectively.

The general object of this invention, therefore, is to provide a wringer of the rotary pressure roll 10 type, which will prevent injury to the operator, and which will permit the operator to straighten the clothes and fix the buttons without fear of injury.

A further object is to provide a wringer of the 15 rotary pressure roll type, which may be power-driven and wherein material may be selectively fed from either of two opposite faces without the employment of clutches, reverse gear mechanisms, etc.

A more specific object is to provide a wringer 20 having a pair of pressure rolls and auxiliary rolls, which are arranged to feed material into the bite of the pressure rolls with suitable mechanism to control and guide the material entering and passing from the bites of the various rolls.

Another object of the present invention is to provide an efficient wringing mechanism which eliminates the multiplicity of controls such as 30 clutches, reverse gears, etc., found in the ordinary wringer, and so construct such improved wringer as to render it safe for unskilled operation, and which wringer at the same time will be extremely durable and readily used in connection with power washing machines.

Other objects of this invention will become more 35 apparent from the following description relating to the accompanying drawings, the essential novel characteristics thereof will be summarized in the claims.

In the drawings, Fig. 1 is a plan view of my improved wringer; Fig. 2 is a side elevation of the wringer, shown in Fig. 1, mounted in position on a washing machine; Fig. 3 is a vertical section as indicated by the lines 3—3 on Fig. 1; Figs. 4, 5, 6 45 and 7 are transverse vertical sections, as indicated by the correspondingly numbered lines on Figs. 1 and 3; Figs. 8 and 9 are longitudinal horizontal sections, as indicated by the correspondingly numbered lines on Fig. 4; Fig. 10 is a detail section, as indicated by the lines 10—10 on Fig. 9.

Referring again to the drawings, it will be noted that my improved wringer comprises a frame, generally indicated at 15, which houses a pair of wringer or pressure rolls 10 and 11 and a pair of auxiliary rolls 12 and 14, one of which is asso-

ciated with each wringer roll, and so mounted that they may be separated therefrom.

As shown in the drawings, the wringer frame 5 comprises a pair of spaced end members 20, which are joined together by suitable cross frame members, such as the webs 21 and 22. I prefer to form these frame members as one unit, such as, a casting, for instance. The upper face of the frame is open and is provided with a frame cap or cover 23, pivoted at 24 to the main frame 15, so that 10 it may be rocked from the position shown in full lines in Fig. 5 to the position shown in the dotted lines. The purpose of this rocking movement will be hereinafter more fully described.

As shown in Figs. 2 and 9, the left-hand frame 15 member 20 is provided with a boss-like extension 26, arranged to be secured by means of suitable bolts 127 to the upper housing 128 of a driving mechanism, similar to that used in present-day wringers, and therefore not described in detail. 20 This housing 128 serves to support the wringer in the same manner as in washing machines of the present-day construction.

The rolls 10 and 11, which are the pressure rolls, are mounted in the same horizontal plane, 25 instead of in a vertical plane, as has been customary in the past. The rolls 10 and 11 comprise the usual rubber wringer rolls 27, which are rigidly secured to suitable shafts 28 and 29. The shafts 28 and 29 are so mounted that the 30 rolls are resiliently urged into contact with each other in a horizontal plane. As shown in Figs. 4 and 6, each end of the shaft 29 of the rear wringer roll 11 is mounted in a bushing 30. The bushings 30 are supported by suitable bearing 35 members 31, which in turn are rigidly secured by suitable screw bolts 32 to the frame cap 23 heretofore mentioned. The forward wringer roll 10 is mounted at either end in bushings 34, which are supported by bearing blocks 35. The bearing blocks 35 are carried on respective studs 36, 40 each of which is slidably mounted in respective socket members 37, which are pivoted on a rod or cross-frame member 38, in such a manner that the roll may swing about the pivot which lies 45 slightly below the horizontal plane passing through the axis of the two pressure rolls, when the latter are in their normal position as shown in Fig. 4.

The pressure roll 10 is normally urged into 50 contact with the pressure roll 11 by a pair of comparatively strong compression springs 39, which embrace respective studs 36. One end of each spring bears against the respective bearing block 35 and the other end against a suitable shoulder 55

40 formed on the respective pivoted bearing members 37 heretofore mentioned. The arrangement is such that the spring 39 is normally in compression and by adjusting the stud 36 the pressure between the two rolls 10 and 11 is readily adjusted.

The pressure rolls 10 and 11 are normally retained in a position with their axes substantially in the same horizontal plane. As shown in Fig. 4 the roll 11 is carried by the pivoted frame cover 23, which is normally retained in contact with the main frame 15 by a pair of latches 42 positioned adjacent opposite ends of the frame. The latches 42 are rigidly secured to opposite ends of a rock shaft 43, supported by the bearings 44 carried by the cover 23. Each latch 42 extends downwardly from the rock shaft 43 and is provided at its lower end with a hook-like nose 45 to engage respective pins 46 carried by opposite end walls of the main frame 15. A suitable spring 47 embraces the shaft 43 and is arranged so that one end of the spring coacts with the cover 23 and the other end engages one of the latches 42. This spring acts to retain the latches 42 in engagement with their respective pins 46, thereby maintaining the cover 23 in engagement with the main frame 15.

The position of the pressure roll 11 is fixed relative to the cover 23 by reason of its bearings 32 being secured to the cover plate, as heretofore described. The pressure roll 10 is pivoted on pins 38 heretofore mentioned and which are carried by the main frame 15. Each bearing member 35, which supports the roll 10, is provided with a pin 48 which engages a wearing plate 49, secured to the cover 23 by bolts 32 heretofore described. The pin 48 is of such a height that it permits the roll 10 to lie slightly above a plane passing through the pivots 38 of the pressure roll 10 and the axis of the other pressure roll 11. The purpose of this arrangement will be hereinafter more fully described. The lower surface of the bearing block 35 engages the upper surface of respective bracket members 50 which are rigidly secured to the main frame 15 by suitable bolts 51. This arrangement positively locates the axis of the roll 10 and prevents such roll from swinging about its pivot when the cover 23 is retained in its normal or closed position by the latches 42.

The auxiliary rolls 12 and 14 are positioned beneath, and are arranged to coact with, respective pressure rolls to guide the clothes or material into the bite of the pressure rolls 10 and 11. The rolls 12 and 14 are made of any softer suitable material. However, I prefer to use a material that is used for the pressure roll, preferably rubber, so that should the operator's fingers be caught between an auxiliary roll and its respective pressure roll, there will be no substantial injury.

Each auxiliary roll is rigidly secured to a suitable shaft 60, which is journaled at one end in a bearing 61 and at the other end in a bearing 62. The bearings 61 of both auxiliary roll shafts are carried by the bearing blocks 63, while the bearings 62 of such shafts are carried by a bearing block 64. Each bearing block 63 and 64 supports respective ends of both auxiliary roll shafts and maintains the axis of these rolls fixed relative to each other.

The auxiliary rolls are so mounted that they may be raised and lowered relative to the pressure rolls. In addition to the raising and lowering movements, the auxiliary rolls may be rocked

end for end in a substantially universal manner. For this purpose the auxiliary roll shafts 61 are slidably mounted in their respective bearings and the bearing blocks 63 and 64 are mounted in such a manner as to permit them to ride 5 and rock in the frame. As shown in Figs. 4 and 6, the bearing blocks 63 and 64 are mounted in the respective frame brackets 50, heretofore mentioned.

Each bracket 50 comprises a lower member 52 10 which is secured to the base of the main frame 15 by suitable bolts 52a and is provided with a pair of upwardly extending arms 53, which are arranged to embrace opposite ends of respective bearing blocks 63 and 64. The arms of the lower 15 member 52 are bridged by a suitable cap 55 which is secured in position by suitable bolts 51 which coact with the frame and other bolts 51a which coact with the lower bracket member 52.

The bearing blocks 63 and 64 are provided at 20 opposite ends with pin-like extensions 65, which project into the slots 66 formed in the arms 53 of the lower bracket member. This construction permits the bracket members of the bearing blocks 63 and 64 to move upwardly or downwardly 25 individually or simultaneously in their respective bracket members. It likewise permits the bearing blocks to rock substantially universally in the plane of their respective slots 66 and within the confines of their respective bracket 30 member 50.

The auxiliary rolls 12 and 14 rotate in the direction of the arrows shown in Fig. 7. The driving mechanism causing such rotation will be hereinafter more fully described. However, it 35 will be noted in this construction that the material may be fed from either the vertical face 18 or the opposite vertical face 19 of the wringer into the bite of the pressure roll 10 and its auxiliary roll 12 or as shown in Fig. 7, or into the 40 bite of the auxiliary roll 11 and its associated auxiliary roll 14. As shown in Fig. 7, the material is being fed between the bite of the right-hand set of rolls, namely, the pressure roll 11 and the auxiliary roll 14. The action of these 45 rolls is such as will cause the material to pass inwardly towards the center of the wringer where it is gripped by the pressure rolls 10 and 11 and carried upwardly between the bite of such pressure rolls and ejected from the top of the 50 wringer.

A suitable guide or stripping member 70 is provided to strip the material from the auxiliary rolls 12 or 14 and cause such material to enter the bite of the two pressure rolls. As shown in 55 Figs. 3, 4, 7, 9 and 10 there is a guide 70 comprising a longitudinally extending bar, which is mounted in the space between the four rolls and has a downwardly extending portion 71 which projects between the two auxiliary rolls 60 and outwardly extending portions or stripping edges 72 and 73, which engage the auxiliary rolls 12 and 14 respectively to strip the material therefrom.

The guide 70 is mounted in the bearing blocks 65 63 and 64, and therefore will follow the movement of the auxiliary rolls and the edges 72 and 73 of the guide will remain in contact with their respective rolls. The guide 70, bridging, as it does, the gap between the two auxiliary rolls, 70 thus prevents the material from dropping or from being carried downwardly between such rolls, and together with the direction of rotation of the various rolls, causes such material to enter the bite of the two pressure rolls.

The guide 70 extends the full length of the rolls and is provided on either end with an extension or ear 74, each of which is mounted between corresponding pairs of outwardly extending arms 75 carried by the bearing brackets 63 and 64. It will be noted that the guide 70 rests by its own weight upon the auxiliary roll. Hence, any variation in the diameter of the rolls, due to climatic conditions or to wear, is automatically compensated for. The slot 76 between the arms 75 of each bearing block 63 or 64 is readily capped by a suitable cap member 76a which serves to prevent excessive upward movement of the guide member and aids materially in the assembling of the structure. It will be noted that each slot 76 extends some distance above and below the respective extensions 74 of the guide. Hence, if for any reason material should become wedged or caught between the guide and the roll, the guide will readily rise in the slot, preventing any damage to the material.

It will be noted from Fig. 7 that the guide is in the form of a ridge having an upwardly projecting ridge-like portion 77, which projects upwardly toward the two pressure rolls 10 and 11. The surface of the guide between the upwardly extending ridge 77 and the two stripping edges 72 and 73 are curved to substantially follow the contour of the pressure rolls 10 and 11. However, this guide may be of substantially any shape which contacts with the two auxiliary rolls and bridges the gap therebetween.

The auxiliary rolls 12 and 14, together with the guide member 70, are normally urged upwardly so that the auxiliary rolls contact their respective pressure rolls 10 and 11 through their entire lengths. As shown in Figs. 4 and 6, suitable compression springs 78 are carried in recesses in the lower bracket members 50 and seat in suitable recesses in the lower surface of the respective bearing blocks 63 or 64. These springs 78 are comparatively light and of sufficient strength only to maintain contact between the rolls and to maintain a driving relationship therebetween so that material will feed into the bite of the two pressure rolls. Hence, if the operator's fingers are at any time caught between an auxiliary roll and its respective pressure roll they may be readily withdrawn without any danger whatsoever.

I further provide my improved wringer with an additional safety device, which automatically releases the pressure between the various rolls when either one or the other of the auxiliary rolls is depressed a predetermined distance, which distance is, of course, greater than the distance that the roll is ordinarily depressed during normal wringing operations. I have likewise arranged this mechanism so that the pressure between the two pressure rolls and between the auxiliary rolls and the corresponding pressure rolls may be manually released at any time by the operator to prevent injury or anticipated injury to either the operator or to the material being fed to the wringer.

The manual release enables the operator to readily separate the rolls in instances of anticipated injury. This release is best shown in Figs. 2, 3, 4, 5 and 7. As shown, the manual release comprises a pair of independent plungers 80, slidably mounted in the upper frame plate adjacent opposite ends thereof, and provided on their upper ends with buttons 81 which may readily be depressed manually by the operator. The lower edge of each plunger 80 is provided

with an enlarged shoulder-like portion 82 which engages respective outwardly extending arms 83 integral with the latch members 42, heretofore described. Downward pressure upon either of the buttons 81 will cause both latch members 5 to rock counter-clockwise and become disengaged from their respective pins 46.

The release of the latch members 42 causes the compression springs 39 and 78 to act simultaneously to move the cover 23 together with its 10 pressure roll 11, and the pressure roll 10 upwardly, relieving substantially all pressure between the rolls. As heretofore mentioned, the axis of the pressure roll 10 is slightly above a 15 plane passing through the pivots 38 of the pressure roll 10 and the axis of the pressure roll 11. Hence, the action of the compression spring 39 is such as to force the pressure roll 10 upwardly.

I find that when my improved wringer is released, the action of the compression spring 39, 20 due to its strength, causes the cap member 23, together with the roll 11, to fly open with considerable speed. This condition is desirable, as it makes the release practically instantaneous. However, I find it advantageous to limit the 25 movement of the cover 23 to prevent damage to the parts. For this purpose there is pivotally mounted on the cap member 23 a pair of depending hook-like members 84 which, when the cover is in raised position, as shown in dotted 30 lines in Fig 5, engage pins 86 carried by the end plate members of the frame 23. These hook-like members are normally retained in contact with their respective pins by suitable springs such as that shown in Fig. 5, at 86a. 35

After the wringer has been released, it may readily be returned to normal position by merely pressing downwardly upon the cap member. For this purpose, the latches 42 are provided at their lower ends with camming surfaces 87, 40 which engage the pins 46 heretofore described and cam the latches back into position, permitting the springs 47 to restore the latch to a latched position, thereby again locking the wringer in its normal and operative position. 45

Consequent upon an excess or abnormal separation of an auxiliary roll from its associated pressure roll, the pressure between the various rolls will be automatically released. To accomplish this, each bearing block 63 and 64 is provided with outwardly extending lugs 88 (Figs. 4, 5 and 9). These lugs normally overlie inwardly extending arms of bell cranks 89 which are rigidly secured to a rock shaft 90 supported in bearing extensions 91 (Fig. 6) of the bearing bracket 50. Each of the bell cranks 89 is provided with an upwardly extending arm 91 which arms are arranged to engage lips 92 of their respective latch members 42. Hence, when the pressure roll or an auxiliary roll has been separated from its associated pressure roll a distance which would cause the lugs 88 to contact with the bell crank 89, the latter will rock in a clockwise direction, Fig. 5, against the action of the spring 94. The upper arms 91 of the bell crank will then 60 rock the latch members 42 counter-clockwise, disengaging them from their respective locking pins 46, thereby permitting the springs 39 and 78 to separate the rolls, as heretofore described in connection with the manual release. 65 70

The rotation of the rolls may be operated from any suitable power mechanism, well known, such as, for instance, a vertically extending power shaft 100, carried in a suitable casing 101, which rises above the tub 102 of the usual washing 75

machine. Mounted on top of the housing 101 is a gear box 111, in which is mounted a bevelled gear 112, which is rigidly secured to the power shaft 100 and meshes with a similar bevelled gear 113 mounted on a shaft 114 which is supported in suitable bearings and enclosed within the housing 111.

As shown in Figs. 2, 5, 8 and 9, the shaft 114 extends inwardly through the end walls of the 10 wringer frame 15. Rigidly secured to the inner end of the shaft 114 by a suitable bolt 115 is a spur gear 116, arranged to mesh with a spur gear 117, which is rigidly secured to the shaft 29 of the pressure roll 11. This arrangement provides a 15 direct drive from the power shaft to the pressure roll without the use of any clutches, reverse gear or similar mechanism.

The requirement of a reverse gear drive is entirely eliminated by the roll arrangement which 20 permits the material to be fed from either of two opposite directions of the wringer without the necessity of the reversal of the direction of rotation of the rolls. The pressure roll 10 is, in turn, frictionally driven through the medium of the 25 pressure roll 11.

The requirement for clutches between the power mechanism and the wringer is eliminated by the release mechanisms. Whenever either the 30 manual or the automatic release is operated, the gear 117, which is carried by the shaft 29 of the pressure roll 11, is carried out of mesh with the driving gear 116, thereby breaking the driving connection to all of the wringer rolls.

The springs 18, which maintain the auxiliary 35 rolls in contact with their respective pressure rolls, are comparatively light to eliminate danger to the operator when the fingers are caught between a pressure roll and its associated auxiliary roll. I therefore find it convenient to gear the 40 two auxiliary rolls together, as by gears 120, so that each auxiliary roll may be driven at all times through the other auxiliary roll, which will be in direct frictional contact with its respective pressure roll, while the former auxiliary roll will be 45 in contact with its respective pressure roll only through the medium of the material being fed therebetween. I find that such an arrangement greatly aids in proper feeding of the material between the auxiliary rolls and their respective 50 pressure rolls with a minimum amount of pressure between such rolls. This, of course, is highly desirable, as it greatly adds to the safety of the wringer.

I find it advantageous to provide a take-off 55 guide or stripper member for each pressure roll to prevent material being ejected from the wringer, from following the circumference of the pressure rolls. Such guides are best shown in Figs. 1 and 7, and comprise curved plates 130 60 pivoted adjacent the upper surface of the frame cap 23 as at 131 and having downwardly projecting edges 134 which are normally held in engagement with their respective pressure rolls by suitable tension springs 135, one end of each of which 65 is secured to its respective guide and the other to a pin carried by the cap member 23.

I also provide a deflector member to positively 70 guide the ejected material toward the face of the wringer opposite the face from which the material is being fed. To this end I provide a plate-like member 140, which is pivoted as at 141 above and substantially in line with the bite of the pressure rolls 10 and 11. This deflector plate is so arranged that it may be swung about 75 its pivot from the position shown in full lines

in Fig. 7 to the position shown in dotted lines, thereby causing the material which is stripped from the roll 10 or 11 to follow the deflector plate and be guided thereby to the side of the wringer opposite the side into which the material is being fed.

I likewise find it desirable to arrange my improved wringer so that when material is fed from one side of the wringer, the opening in the frame on the opposite side will be closed, to prevent the material which has been wrung from again entering the wringer structure and being caught between the rolls on the opposite side. To this end I provide a pair of plate-like members 150, each of which is shaped to close the respective openings 151 in the sides of the wringer through which the material is fed to the roll. The plates 150 are pivoted as at 152 to the wringer frame and are connected by respective links 153 to opposite ends of a drain board 160, in such a manner that one plate 150 will be in position to close the opening in one side of the wringer, while the other plate will be swung about its pivot to a position exposing the opening on that side of the wringer. The plates or guard members 150 are operatively swung to expose either side of the wringer by the drainboard 160, as will be hereinafter more fully described.

The drainboard 160 is primarily provided to divert the water, being wrung from the materials, toward that side of the wringer into which such materials are being fed, and return such water or liquid to the tub, in connection with which the wringer is being used. As shown in Fig. 7, the bottom wall of the wringer frame 15 is provided with a centrally disposed longitudinally extending opening 161, through which the waste liquid passes from the frame. To facilitate the passage of this waste liquid, the bottom walls 162 of the frame 15 slope towards the opening 161.

The drain board is positioned below the opening 161 and arranged to selectively divert the water which passes through the opening to either side of the wringer, as desired. As shown in Figs. 1, 2, and 7, the drain board comprises a plate-like trough 160, which extends, longitudinally from one end of the opening 161 to the other and transversely to points beyond both outer faces of the wringer. The drain board is provided at its ends with upturned flanges 163, through which passes a rod 164 carried by the frame 15, thus providing a pivoted mounting for the drain board, whereby it may be swung to divert the water either to the right, as shown in Fig. 7, or to the left, as desired.

A suitable latch mechanism may be provided to retain the drainboard in its adjusted position. As shown in Fig. 7, suitable knobs 170 are pressed outwardly from the side flanges 163 of the drain board and are arranged to engage depressions 171 formed in end frame members 172. The resiliency of the material permits ready engagement and disengagement of the latch members by the depressing or raising of the drain board by the operator.

As heretofore mentioned, the guard members 150, which prevent materials which have been wrung from again entering the wringer, are connected to the drainboard by links 153. As shown in Fig. 7, one end of each link 153 is pivotally connected, as at 154, to its respective guard plate 150, and the other end of each link is pivotally connected as at 155 to the drainboard 160 adjacent the respective side of the wringer. The arrangement is such that when the drain-

board is positioned, as shown in Fig. 7, to divert the waste liquid to the right-hand side of the wringer, the guard plate 150 on the right-hand side of the wringer is open.

5 When the position of the drain board is reversed, that is, rocked to divert the water toward the left-hand side of the wringer, the positions of the guard plates 150 will also be reversed, the left-hand guard being opened and the right-hand guard being closed. This mechanism prevents the operator from thoughtlessly failing to properly position the drain board and permit the water to fall to the floor, rather than return to the tub, as material cannot be fed to the wringer unless the drain board is positioned to divert the waste water toward the feeding side of the wringer.

From the foregoing description, it will be seen that I have provided an efficient wringing mechanism which eliminates the multiplicity of controls, such as clutches, reverse gears, etc., found in the ordinary wringer. I have likewise constructed my improved wringer in such a manner as to render it safe for unskilled operation, and have, at the same time, provided a wringer which is extremely durable and which may readily be used in connection with present-day power washing machines.

I claim:

30 1. In a wringer, a frame, a pair of pressure rolls mounted in said frame and having an upwardly extending bite, a pair of spaced plate-like stripper members pivotally mounted in said frame, means to maintain one edge of each of said stripper members in contact with respective pressure rolls, a deflector plate pivotally mounted in said frame and having one edge thereof arranged to be swung into engagement with either of said members, whereby material 40 is stripped from either of said rolls and is diverted to either side of the wringer as desired.

2. In a wringer, a pair of pressure rolls having an upwardly extending bite, a pair of stripper members, resilient means to maintain said stripper members in contact with their respective rolls, a deflector plate pivotally mounted on an axis lying in a vertical plane passing between and substantially parallel with the lines of contact of said stripper members with their respective rolls, said deflector plate extending downwardly below its pivot and arranged to be swung into position with its lower edge adjacent either stripper member desired, whereby material may be selectively diverted to either side of the wringer.

3. A frame having openings in opposite side walls, a pair of pressure rolls mounted in said frame, means to guide material fed through the opening in either of said walls into the bite of said rolls, means cooperating with said walls respectively to selectively close the openings therein, and means coacting with said last-named means to maintain the opening in one of said walls open when the opening in the other of said walls is closed.

4. In a wringer, a frame including a pair of opposing side walls having openings therein, a pair of pressure rolls mounted in said frame with their axes in substantially the same horizontal plane, means carried by said frame to guide material fed through the opening in either of said side walls into the bite of the pressure rolls, a movable closure for each of said openings, means interconnecting said closure means to move one of said closures to close the opening

in the one of said walls on the opposite side of the wringer from which clothes are to be fed and simultaneously maintain the other closure member in an inactive position relative to the opening in its respective side wall.

5. In a wringer, a frame, a pair of pressure rolls mounted in said frame with their axes in the same horizontal plane, a supplemental roll substantially beneath each pressure roll and coacting therewith to provide a pair of horizontal bites projecting towards opposite sides of said frame, whereby material may be fed into said wringer from either of said opposite sides of said frame, means movably carried by said frame to selectively block respective horizontal bites to prevent material from entering either of said horizontal bites as desired.

6. A wringer comprising a main frame including a top wall, and a pair of substantially vertical side walls, each of said walls having a longitudinally extending opening therein, a pair of coacting pressure rolls having an upwardly extending bite mounted in said frame with said bite beneath the opening in said top wall, a pair of auxiliary rolls mounted in said frame and positioned substantially below respective pressure rolls, resilient means acting to maintain said auxiliary rolls in contact with their respective pressure rolls, thereby providing horizontal bites extending toward the openings in respective side frames, and means whereby material can only be fed into one horizontal bite at a time.

7. In a wringer, a frame having openings in its opposite sides, a pair of pressure rolls mounted in said frame to receive material from either of said opposite sides thereof as desired, a drainboard mounted on said frame to be tilted downwardly towards either of said opposite sides to divert water to either side of the wringer as desired, and means connected to said drainboard to close the opening in the side wall of the frame opposite the side toward which said drainboard is tilted to drain liquid coming from the wringing operation.

8. A wringer comprising a main frame including a top wall and a pair of substantially vertical side walls, each of said walls having an opening therein, a pair of coacting pressure rolls having an upwardly extending bite mounted in said frame with said bite beneath the opening in said top wall, a pair of auxiliary rolls mounted in said frame and positioned substantially below respective pressure rolls, resilient means acting to maintain said auxiliary rolls in contact with their respective pressure rolls to provide a horizontal bite extending toward the opening in respective side walls, means to close the openings in said side walls, a drain board pivotally mounted below said auxiliary rolls, and means interconnecting said closure means with said drainboard to close the opening in one side wall and remove the closure from the opening in the other side wall when the drainboard is tipped to drain toward the last mentioned side wall.

9. A wringer comprising a main frame, four rolls mounted in said frame and coacting to provide a vertically extending bite and a pair of horizontally extending bites wherein material fed into either of said horizontally extending bites is ejected out of the pass of said rolls upwardly through said vertically extending bite, means to selectively close either of said horizontally extending bites to prevent the passage of material therethrough, means to divert the material ejected from said upwardly extending bite toward oppo-

site faces of the wringer as desired, and means to deflect the liquid wrung from such material toward either face of the wringer as desired.

10. In a wringer, a main frame, a cover pivotally connected to said frame, a pressure roll carried by said cover and extending downwardly into said main frame, a second pressure roll pivotally carried by said main frame, means to maintain said cover in position on said main frame and thereby 10 position the axes of said rolls and the last-named pivot in substantially the same horizontal plane.

11. In a wringer, a main frame, a cover hinged to said frame, a pressure roll pivotally carried by said main frame and spring pressed toward the 15 hinge, a second pressure roll carried by said cover and extending downwardly into said main frame, between the hinge and the first-mentioned roll; and releasable means to maintain said cover in position on said main frame.

12. In a wringer, a main frame, a member pivotally mounted on said main frame, a pressure roll carried by bearings with said pivoted member, a second pressure roll carried by bearings pivotally connected to said main frame, releasable 25 means to maintain said member in position on said main frame, and means to prevent the swinging of said last-named pressure roll about its pivot when said member is so maintained.

13. In a wringer, a main frame having an open 30 top, a cover member pivotally mounted on said main frame to substantially close the top thereof, a pressure roll carried by bearings rigid with said pivoted cover, a second pressure roll carried by bearings pivotally connected to said main frame, releasable means to maintain said cover in position 35 on said main frame, means to prevent the swinging of said last-named pressure roll when said cover is closed, said means being positioned to maintain said pivoted roll substantially in a horizontal plane passing through the axis of said first-named pressure roll and resilient means to urge said last-named roll into contact with the first-named roll.

14. In a wringer, a main frame, having an open 45 top, a cover member having an opening in its upper face pivotally mounted on said main frame to substantially close the top thereof, a pressure roll carried by bearings rigid with said pivoted cover, a second pressure roll carried by bearings pivotally connected to said main frame, means to prevent the swinging of said last-named pressure roll when said cover is closed, said means being positioned to maintain said pivoted roll substantially in a horizontal plane passing through the axis of said first-named pressure roll whereby an 50 upwardly extending bite is provided, resilient means to urge said last-named roll into contact with the first-named roll, and means carried by said frame and resiliently urged into contact 55 with said pressure rolls to guide material fed from opposite vertical faces of said frame into the bite of said rolls.

15. In a wringer, a main frame having an opening 60 in one wall thereof, a cover member for said wall, said cover being pivotally mounted on said main frame to substantially close said opening, a pressure roll carried by said pivoted cover, a shaft integral with said roll, a gear on said shaft, a second pressure roll carried by said main frame, releasable means to maintain said cover in position 65 on said main frame, a gear carried by said main frame and meshing with said first-named gear when said cover is closed and separated from said first-named gear when the cover is open, power means to drive the second-named gear, 70

whereby when said cover is opened the driving connection to said roll is broken.

16. In a wringer, a frame, a pressure roll carried thereby, a second pressure roll, contacting with said first-named roll, bearings for said last-named roll, a pair of arms connected at one end to said bearings and connected adjacent their other ends to said frame, each of said arms comprising two interconnected members, one of said members being slidable relative to the other member, means to limit the sliding movement of said members, and resilient means acting to lengthen said arms and thereby resiliently maintain said rolls in contact with each other. 5

17. In a wringer, a main frame, a cover pivotally connected to said frame, a pressure roll carried by bearings rigid with said cover and extending downwardly into said main frame, a second pressure roll, bearings for said last-named roll, a pair of arms connected at one end to said bearings and pivoted adjacent their other ends to the main frame, each of said arms comprising two members, one slidable relative to the other, means to limit the sliding movement of said arms, resilient means acting to lengthen said 20 arms, the pivots for said arms being substantially in the horizontal plane passing through the axis of the first-named pressure roll, a stop to limit the downward movement of said arms, means carried by said cover to normally maintain said 25 pivoted roll in its lowermost position, said stop arranged to maintain the axis of said pivoted roll above said horizontal plane, the axis of the first-named roll and the axis of said pivot being spaced apart a distance less than the maximum 30 length of said arms plus the radius of each of said rolls, and a releasable means to maintain said cover in engagement with said main frame, whereby, when said last-named means is released, said resilient means acts to open said 35 cover. 40

18. In a wringer, a frame having an opening, a cover for said opening, a pair of pressure rolls in said frame, a guide carried in said frame and positioned to coact with one of said pressure rolls to provide a bite therewith, means to permit said guide to move away from said pressure rolls when an excess thickness of clothing is fed to the bite therebetween and means operated by said separating movement to open said cover. 45

19. In a wringer, a pair of pressure rolls disposed in the same substantially horizontal plane, power means to drive said rolls, an auxiliary roll disposed adjacent and normally in contact with one of the pressure rolls and separable therefrom, wherein the work passes first between such auxiliary roll and its associated pressure roll and then between the two pressure rolls, and means acting upon a predetermined separation between the auxiliary roll and its coacting pressure roll 55 to stop the rotation of both the pressure rolls. 60

20. In a wringer, a pair of pressure rolls disposed in a substantially horizontal plane, power means to drive said rolls, means to guide clothes into the bite of said pressure rolls from either side of the wringer, means to urge said guide means toward said pressure rolls and means acting upon movement of said guide means away from either pressure roll to stop the rotation of both the pressure rolls. 65

21. In a wringer, a frame, a member pivotally carried by said frame, a pressure roll carried by said member, a second pressure roll carried by said frame, said rolls being adapted to coact to wring material, resilient means to urge said rolls 70 75

together, means to lock said rolls in coacting relation, one of said rolls being positioned when coacting with the other to lie slightly without a plane passing through the pivot of said member 5 and the axis of the other roll, whereby when said locking means is released said resilient means acts to rock said member about its pivot.

22. In a wringer, the combination of a pair of pressure rolls, a pair of supplemental rolls, resilient means to cause relative movement between the supplemental rolls and their respective pressure rolls to cause a contact between the supplemental rolls and their respective pressure rolls, a power operable mechanism, a separable connection between said mechanism and said pressure rolls to normally rotate both of said rolls, and means to separate said connection to interrupt the application of power to said rolls consequent upon a predetermined separation between 20 either supplemental roll and its associated pressure roll.

23. In a wringer, a pair of pressure rolls, feeding means to feed material into the bite of said pressure rolls, said feeding means and one of said pressure rolls being arranged for relative yielding movement toward each other, a power operable device, a power connecting member adapted to selectively couple said device to the pressure rolls to cause them to be rotated, and means actuated by a predetermined separation between said feeding means and its coacting pressure roll to uncouple the power connecting member from said wringer rolls.

24. In a wringer, a pair of pressure rolls 35 mounted in substantially the same horizontal plane, a power operable driving mechanism, a separable driving connection between said mechanism and one of said pressure rolls, means to guide material from the side of the wringer into the bite of the two pressure rolls, wherein the material passes upwardly between the coacting pressure rolls, and means to separate said driving connection consequent upon the passing of a predetermined thickness of material to the 40 guiding means.

25. In a wringer, a pair of coacting pressure rolls, a pair of auxiliary rolls, each auxiliary roll being normally in contact with its corresponding pressure roll and separable therefrom, whereby 50 the work passes first between an auxiliary roll and associated pressure roll, and then between the two pressure rolls, and means acting upon a predetermined separation between an auxiliary roll and its associated pressure roll to automatically cause the pressure between the auxiliary rolls and their 55 pressure rolls to be relieved.

26. In a wringer adapted to receive clothes from either side, a pair of coacting pressure rolls, a pair of auxiliary rolls, each auxiliary roll being 60 normally in contact with its corresponding pressure roll and separable therefrom, whereby the work passes first between an auxiliary roll and associated pressure roll, and then between the two pressure rolls, and means acting upon a predetermined separation between an auxiliary roll and its associated pressure roll to automatically cause the pressure between the pressure rolls to be relieved.

27. In a wringer, the combination with a main 70 frame of a pressure roll carried thereby, a supplementary frame pivotally secured to the main frame, a second pressure roll mounted in the supplementary frame, an auxiliary roll mounted parallel with one of the pressure rolls, said 75 auxiliary roll arranged to normally contact with

its coacting pressure roll and separable therefrom, and means whereby a predetermined amount of separation between the auxiliary roll and its associated pressure roll will cause the supplementary frame to swing about its pivot. 5

28. In a wringer, the combination of a main frame, a supplementary frame pivotally secured to the main frame, a pressure roll mounted in the main frame, a second pressure roll mounted in the supplementary frame and adapted to coact with the first-named roll, resilient means adapted to retain the two rolls in contact with each other, a pair of auxiliary rolls mounted below the pressure roll and normally retained in contact therewith, a latch to retain the auxiliary frame 10 in its normal position wherein each auxiliary roll is in contact with its associated pressure roll, and means whereby a predetermined amount of separation between an auxiliary roll and its associated pressure roll will cause the latch to release 15 the supplementary frame and relieve the pressure between a pair of rolls. 20

29. In a wringer, the combination of a pair of pressure rolls, a pair of auxiliary rolls contacting with the pressure rolls respectively, a guide disposed between the four rolls, a pair of rigid bearing members supporting the auxiliary rolls and guide at their ends, and resilient means to support the bearing members in such manner that the rolls and guide may move substantially as a unit 25 and substantially universally relative to the pressure rolls. 30

30. In a wringer, the combination with a frame, of a pair of pressure rolls, an auxiliary roll adapted to coact with one of said pressure rolls, 35 a guide adapted to guide the work from between a pressure roll and the auxiliary roll into the bite of the two pressure rolls, a mounting for said auxiliary roll and said guide, resilient means disposed between said mounting and said frame 40 and adapted to retain the auxiliary roll in contact with one of the pressure rolls, said guide having two edges adapted to coact with the auxiliary roll and one of the pressure rolls respectively, and means whereby the auxiliary roll and 45 the guide may rock as a unit in two directions, the planes of said movements being substantially normal to each other.

31. In a wringer, the combination of a pair of pressure rolls, an auxiliary roll contacting with 50 one of the pressure rolls, a rigid guide disposed adjacent the rolls, a pair of rigid bearing members supporting the auxiliary roll, resilient means to support the bearing members, whereby the auxiliary roll may move substantially universally 55 relative to the pressure rolls, and means adapted to be acted on by the bearing member to relieve the pressure between the pressure rolls.

32. In a wringer, the combination with a frame, of a pair of pressure rolls, a pair of auxiliary rolls 60 disposed beneath and adapted to coact with one of said pressure rolls respectively, a rigid guide adapted to guide the work from between a pressure roll and an auxiliary roll to the pressure rolls, a mounting for said auxiliary rolls and said 65 guide, resilient means disposed between said mounting and said frame and adapted to retain the auxiliary rolls in contact with the pressure rolls, said guide having three edges, one edge adapted to coact with each supplemental roll respectively, the other edge adapted to coact with the pressure rolls, wherein the supplemental rolls and the guide may rock as a unit in two directions, the planes of said movements being substantially normal to each other, and means to 70 75

restrain the movement of the supplemental rolls in a plane parallel to a plane passing through the axis of each pressure roll.

33. In a wringer, the combination with a pair of pressure rolls, of a frame carrying one of the pressure rolls and mounted on an axis parallel with the rolls and pivoted eccentrically thereof, resilient means tending to press the rolls together, an auxiliary roll adapted to coact with one of the pressure rolls, said auxiliary roll so arranged that its surface may be moved away from such pressure roll, and means acting automatically upon a predetermined separation of said rolls to release said frame carrying one of the pressure rolls.

34. In a wringer, a main frame, a pair of supplemental frames pivotally carried by the main frame, a pressure roll rotatably mounted on each supplemental frame, resilient means to cause one pressure roll to contact with the other pressure roll and normally acting to cause one supplemental frame to rock about its respective pivot, and a latch mechanism normally acting to restrain the supplemental frame against movement due to the action of said resilient means.

35. In a wringer, a main frame, a pressure roll carried thereby, a supplemental frame pivotally secured to the main frame, a second pressure roll mounted in the supplemental frame, an auxiliary roll arranged to normally contact with the pressure roll and separable therefrom, resilient means acting to rock the supplemental frame about its pivot, a pair of bell crank latch members disposed at opposite ends of the main frame and arranged to engage the supplemental frame to retain it against movement about its pivot, each of said latch members being responsive to a predetermined separation between the auxiliary roll and its pressure roll to release the supplemental frame, and means interconnecting said latches to cause the simultaneous release of the supplemental frame.

36. In a wringer, the combination of a frame, a pair of pressure rolls mounted in a horizontal plane in said frame, resilient means adapted to retain the pressure rolls in contact with each other, an independent auxiliary roll associated with and beneath each of the pressure rolls, said auxiliary rolls being spaced apart from each other, resilient means adapted to retain the auxiliary rolls in contact with their respective pressure rolls, a rigid guide member disposed between the four rolls and wherein the work may be fed from either side of the frame between one pressure roll and one auxiliary roll, thereafter guided into the bite of the two pressure rolls and ejected from the wringer.

37. In a wringer, the combination of a pair of pressure rolls, a pair of auxiliary rolls contacting with the pressure rolls respectively, a guide in the form of a ridge projecting toward the pass of the pressure rolls, a pair of rigid bearing blocks supporting the guide at its ends and carrying the journals for the two auxiliary rolls, and springs for supporting the two rigid bearing blocks, whereby an auxiliary roll and the guide may be moved as a unit.

38. In a wringer, the combination of a pair of pressure rolls, a pair of auxiliary rolls beneath and contacting with the pressure rolls respectively, a guide in the form of a ridge projecting toward the pass of the pressure rolls and with its outer edges adjacent to the periphery of the auxiliary rolls, and devices for carrying the two auxiliary rolls and the ridge-guide as a unit and

preserving them in a fixed relation to each other, and means for yieldingly supporting said devices.

39. In a wringer, the combination of a pair of pressure rolls, an auxiliary roll contacting with one of the pressure rolls, a concave guide located adjacent said auxiliary roll and the corresponding pressure roll and having a concave surface substantially parallel with one of the pressure rolls, and rigid means connecting the guide and the journal of said auxiliary roll and yieldingly supporting them independently of the pressure rolls so that the guide and auxiliary roll may move bodily away from the corresponding pressure roll.

40. In a wringer, the combination of a pair of pressure rolls, a pair of auxiliary rolls respectively contacting with the pressure rolls, a concave guide located in the region between the auxiliary rolls and the pressure rolls and having a concave surface substantially parallel with one of the pressure rolls, and rigid means connecting the guide and the journals of the auxiliary rolls and yieldingly supporting them so that the guide and auxiliary rolls may move bodily away from the corresponding pressure roll.

41. In a wringer, the combination of a frame, a pair of pressure rolls mounted in said frame, resilient means adapted to retain the pressure rolls in contact with each other, an independent auxiliary roll associated with each pressure roll, resilient means adapted to retain the auxiliary rolls in contact with their respective pressure rolls, and a guide member disposed between the four rolls and lying against the auxiliary rolls, and wherein the work may be fed from either side of the frame, between one pressure roll and one auxiliary roll and thereafter guided into the bite of the pressure roll and ejected from the wringer.

42. In a wringer, the combination of a pair of pressure rolls, a pair of auxiliary rolls contacting with the pressure rolls respectively, a guide in the form of a ridge projecting toward the pass of the pressure rolls, a pair of rigid bearing blocks supporting the guide at its end and carrying the journals of the two auxiliary rolls, and springs for supporting the two rigid bearing blocks, whereby an auxiliary roll and the guide may be moved as a unit.

43. In a wringer, a pair of pressure rolls disposed in a substantially horizontal plane, power means to drive said rolls, means to guide clothes into the bite of said pressure rolls from either side of the wringer, means to urge said guide means and said pressure rolls together, and means acting upon movement of said guide means away from either pressure roll to relieve the pressure between the pressure rolls.

44. In a wringer, a pair of pressure rolls disposed in a substantially horizontal plane, power means to drive said rolls, means to guide said clothes into the bite of said pressure roll from either side of the wringer, means to urge said guide means and said pressure roll together, and means acting upon movement of said guide means away from either pressure roll to stop the rotation of a pressure roll.

45. In a wringer, the combination of a frame, a pair of pressure rolls, a pair of auxiliary rolls, a pair of end members movably mounted in the frame and arranged to support said auxiliary rolls, a guide disposed between the four rolls and carried by said end members, and a pair of springs mounted in said frame and arranged

to support respective end members between the axes of said auxiliary roll.

46. In a wringer, a frame, a pair of pressure rolls mounted in a substantially horizontal plane to said frame, a pair of auxiliary rolls disposed beneath and normally in contact with respective pressure rolls, the axes of each auxiliary roll being in a substantially vertical plane passing through the axis of the respective pressure rolls, said auxiliary rolls adapted to contact with their respective pressure rolls substantially through-

out the entire length of the pressure roll, a guide disposed between the four rolls and adapted to strip clothes from the auxiliary roll, means to rotate the pressure roll and wherein the work is passed first between either auxiliary roll and its associated pressure roll and then between the two pressure rolls, and is ejected from substantially the top of the wringer without reversing the direction of rotation of any of said rolls. 5
